GRINDING WHEEL DRESSER

Vincent W. Bunker and Martin De Young, Grand Rapids, and Henry W. Kropf, Muskegon Heights, Mich., assignors of one-half to Gallmeyer & Livingston Company, Grand Rapids, Mich., a corporation of Michigan, and one-half to Brickner-Kropf Machine Company, Muskegon Heights, Mich., a corporation of Michigan

Application January 3, 1944, Serial No. 516,784

3 Claims. (Cl. 125—11)

This invention relates to the dressing of grinding wheels and particularly to dressing said wheels in accordance with a predetermined shape or contour.

In the grinding of metals the grinding wheels at their peripheral surfaces may be dressed straight across at right angles to the planes of the sides of the wheel. At other times in order to grind in accordance with certain predetermined shapes or forms the peripheral surfaces of the wheels must be shaped in conformity with such predetermined shapes or forms and it is primarily in connection with dressing such forms that the present invention is concerned.

It is an object and purpose of the present invention to provide a grinding wheel dressing implement in which true and accurate dressing of the peripheral surfaces or edges of grinding wheels may be attained and in accordance with any preselected shape or form. More particularly, the invention is concerned with a dressing implement which requires in its use and operation little or no skill on the part of the operator as the invention which has been produced when once set up for use does not require adjustment or change and is not subject to possible error because of changes or adjustments which must be performed by workmen who can and do frequently make mistakes under such circumstances, and where close accuracy is required.

An understanding of the invention may be had from the following description taken in connection with the accompanying drawings, in which

Fig. 1 is an elevation showing the dressing of a grinding wheel of a predetermined contour, making use of our invention.

Fig. 2 is a fragmentary plan view thereof.

Fig. 3 is a horizontal section substantially on the plane of broken line 3—3 of Fig. 1.

Fig. 4 is an elevation looking at Fig. 1 from the right.

Fig. 5 is a plan view similar to Fig. 2 showing a second embodiment of the invention, and one which may be preferred, and

Fig. 6 is a fragmentary side elevation thereof, similar to Fig. 1.

Like reference characters refer to like parts in the different figures of the drawings.

A fragmentary upper portion of the grinding wheel frame 1 is shown, above which is shown a table 2 upon which work to be processed may be placed. In the disclosure an upwardly extending support 3 extends above the table 2. The grinding wheel 4 fixed upon a horizontal shaft 5 is carried on a supporting housing 6

which may be vertically adjustable upon the member 3 to raise and lower the wheel. It is of course to be understood that in different types of grinding machines the wheel may be vertically adjusted to different positions relative to the table and the work upon the table, or the table may be adjusted to bring the work to the wheel. The present invention is applicable to either type of machine.

10 A hood 7 covers an upper portion of the grinding wheel 4 and at a side thereof has an extension 8, the upper side of which lies in a horizontal plane. At its outer side it is provided with a machined vertical face 9. A horizontal table or platform 10 having a bracket 11 at its under side is connected to the extension 8 of the hood, the inner side of the bracket coming against the vertical face 9 and the platform is securely held in position by a clamping screw 12 which passes through a vertical slot in the bracket 11 and is threaded into the extension 8 of the hood.

At the upper horizontal side of the hood extension 8, at a distance from the inner edges of the table 10, a block 13 is adjustably mounted and secured. Through said block a screw 14 passes, also passing through a lug 15 which extends upwardly from the outer portion of the part 8. A template 16 at its outer edge having the shape or contour in conformity with which the peripheral edge portions of the grinding wheel is to be dressed is held in a clamp 17 which is secured to the block 13 by screws 18, said clamp having a slot for the passage of the screws permitting a short range of lateral adjustment for proper alignment of the template with reference to the sides of the grinding wheel. The template 16 may be adjusted by adjusting the block 13 on which it is mounted through turning the screw 14 and in the dressing of the wheel it is thus adjusted so that its outer edges will lie directly above and tangent to the grinding wheel as it will be after the dressing is completed.

Upon the table or platform 10 the dressing implement is adapted to be placed and moved freely thereover. It includes a part 19 of relatively large area, the under side of which is in a horizontal plane and which lies against the upper side of the platform 10. Integral therewith in the form shown, is an upwardly extending rib 20 which extends beyond the part 19 toward the template 16 on which a guide or feeler 21 is mounted having a knife or chisel vertical edge adapted to be brought against the template 16. 55 The rib 20 is extended in the opposite direction

and then curved downwardly and underneath the platform 10 in an arm 22. At the free end of the arm 22 a holder 23 for a diamond wheel dresser 24 is mounted, the feeler 21 and the holder 23 being one directly over the other.

As previously stated the edge of the template 16 is adjusted or located over the grinding wheel so that such edge at any point will lie directly over the final finished and dressed surface of the wheel in a vertical plane, indicated at A, tangent to the surface of the grinding wheel, such tangent plane being at right angles to the horizontal diameter of the grinding wheel indicated at B. The dressing diamond or equivalent at 24 lies in the plane of the horizontal diameter of the grinding wheel at B.

With this construction and with the parts located as described, the part 19 may be moved over the upper surface of the table or platform 10. And by keeping the vertical knife edge of the feeler 21 against the template the wheel will be dressed with a contour reproducing at any cross section thereof the edge of such template. The feeler 21 and the holder 23 for the dressing point are mounted so that the knife edge of the feeler and the outer point of the diamond 24 lie the one over the other in a plane at an angle of 90° to the surface of base 19 where it engages platform 10.

With this construction of grinding wheel dressing implement the platform or table 10 accurately secured in place and fixed with respect to the grinding wheel axis and the parts 21 and 23 accurately adjusted, there is then required for operation merely the locating of the movable dressing implement upon the platform and with a proper adjustment of the template 16 to a position such that with the feeler 21 against it the dressing of the wheel is accomplished through the diamond 24 coming into an operative dressing engagement therewith. After the wheel has been dressed to a desired outer peripheral contour or shape the immediate movable dressing implement may be removed by merely taking it away from the platform 10, and it may be replaced without requiring adjustment.

In previous dressings of grinding wheels by use of templates as guides and the mounting of the movable dressing implement upon the table of the grinding machine, the table and the wheel being relatively adjustable and movable vertically with respect to each other it has been necessary to very carefully and accurately adjust the table and the wheel with respect to each other so as to properly locate the dressing diamond in proper relation to the axis of the grinding wheel. This difficult operation is avoided with the present invention. Also a greater accuracy in dressing is attained because of a greater stability in that in the dressing the implement consisting of the part 19, rib 20 and arm 22 is relatively heavy and is not subject to vibration or chattering. Furthermore the dressing of the grinding wheel takes place below the template and feeler so that abrasive material cut from the grinding wheel does not come into contact with either the template or feeler, eliminating any danger of harming the edge of the template or contacting edge of the feeler which might occur with the highly abrasive dust falling upon and affecting said template and feeler.

While the disclosure shows and normally in practice, the upper side of the platform 10 will lie in a horizontal plane, therefore, the point of the diamond cutter 24 and the axis of the grinding wheel will lie in a horizontal plane as indi-

cated at B, and the edge of the feeler 21 and the point of the diamond cutter 24 will lie in the vertical plane A, it is to be understood that under other conditions the diamond cutter 24 may engage the grinding wheel at a different position, this being dependent upon the plane occupied by the upper side of the platform 10. If the platform 10 was inclined upwardly and outwardly in Fig. 1 instead of as shown, the diamond cutter 24, would engage the wheel 4 at a point above that shown in Fig. 1, so that a plane including the axis of the grinding wheel and the point of the cutter would be inclined to the horizontal to the same degree or amount that the platform 10 was thus inclined. In such case the template 16 would be moved inward so that the plane indicated at A in which the edge of the feeler 21 and the point of the cutter are located would be inclined to the vertical, with the plane indicated at A at 90° to the plane passing through the axis of the grinding wheel and the point of the cutter 24. Therefore the invention is not necessarily restricted to the upper side of platform 10 lying in a horizontal plane or that the planes B and A shall be horizontal and vertical planes respectively. But in all cases the planes indicated at A and B are at right angles to each other and the plane indicated at B is parallel to the upper surface of the platform 10.

In Figs. 5 and 6 a slightly different embodiment of the invention is shown. The platform 10 is replaced by a platform 100 in which a relatively long and wide arcuate opening 101 is made. The base 19 rests upon the platform in use and its rib 20 above it has opposite extensions each carrying a knife edge feeler 21. From the base 19 a post 220 extends downwardly through the elongated opening 101 and at its lower end carries a head 221 disposed in a generally horizontal position with parts extending in opposite directions from the lower end of the post, in each of which a holder 23 and a dressing point 24 are mounted.

With this construction the base 29 may be moved over the platform 10 so as to keep the feeler at 21 in contact engagement with the edge of the template 16, whereupon the dressing point 24 below will engage the periphery of the grinding wheel and reproduce the contour of the edge of the template at the peripheral edges of the grinding wheel 4. The first dressing of a grinding wheel is a rough dressing and is followed by a finer and more accurate dressing. With the construction shown when the rough dressing has been accomplished, the base 19 and the parts attached and movable therewith are turned through an angle of 180° to bring the opposite feeler 21 against the edge of the template and the opposite dressing point 24 into engagement with the periphery of the grinding wheel.

In both of the constructions shown and described the beneficial results are attained in the same manner. It is to be understood that while in the disclosure the platform 10 is shown as mounted upon a lateral extension to the hood 7 over the upper part of the grinding wheel, such specific arrangement is not necessarily essential to the invention. What is of importance is that the axis of the grinding wheel and the platform 10 over which the base 19 of the dressing implement is moved are held in a fixed relation to each other; and therefore the platform 10 may be mounted in any suitable manner which will maintain this relationship.

It is further to be noted that the block 13 which

carries the template 16, being of relatively light weight and mass, may be very accurately and finally adjusted using the adjusting screw 14 for such purpose. There is no coupling up of the adjustment and positioning of the template with any movement of the relatively heavy table of a grinding machine which in previous grinding wheel dressers, has had to be changed and moved and adjusted in its position in order to bring the dressing diamond cutter at the proper position at the periphery of the grinding wheel. This feature of the invention is productive of greater accuracy and of less deterioration and wear upon the expensive dressing diamonds used, so that they do not need replacement as often as in previous practice.

Having thus described our invention what we desire to claim and secure by Letters Patent is as follows:

1. In a grinding machine, a grinding wheel, a platform secured in fixed relation to the axis of the grinding wheel, a dressing implement having a base with an under side to rest upon and be moved over the upper side of the platform, said dressing implement having a part extending from the base to one side thereof and a part extending downwardly from the base and at its lower portion having an arm extending inwardly toward the grinding wheel, said second mentioned part passing through said platform and said platform having an opening of relatively large size whereby the dressing implement may be moved over the platform, a feeler attached to said first

5 mentioned part and a dressing cutter for the grinding wheel mounted on and extending from the lower free end of said arm, the free edge of the feeler and the outer point of the dressing cutter being disposed in a plane perpendicular to the upper side of the platform.

10 2. A construction containing the elements in combination defined in claim 1, a third part extending from said base opposite the first mentioned part, a feeler attached thereto at its outer end and said second mentioned part at its lower end having a second arm extending opposite from the first arm, and a dressing cutter carried at the outer end thereof.

15 3. An implement for dressing grinding wheels adapted to be moved over a platform held in fixed relation to the axis of the grinding wheel comprising, a base having an under surface to rest upon and be moved over the upper side of the platform, opposite lateral extensions to said base at its front and rear, a feeler connected to the outer end of each of said extensions, a post depending from said base substantially midway between its front and rear and adapted to pass through an opening in the platform, said post at its lower end having a head with oppositely extending arms disposed directly under the platform extensions, each of said arms at its outer end carrying a wheel dressing cutter, as and for the purposes specified.
